(57) CLAIM

The ornamental design for a carrier as shown and described.

DESCRIPTION

FIG. 1 is a front isometric view of a carrier showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures show portions of the carrier that form no part of the claimed design.
